UNITED STATES PATENT OFFICE

169,423

CAROUSEL TOY

Theresa C. Cheresh, Chicago, Ill.

Application October 31, 1951, Serial No. 17,195

Term of patent 7 years

(Cl. D34—16)

To all whom it may concern:

Be it known that I, Theresa C. Cheresh, a citizen of the United States, residing at Chicago, in the county of Cook and State of Illinois, have invented a new, original, and ornamental Design for a Carousel Toy, of which the following is a specification, reference being had to the accompanying drawings, forming a part thereof.

Fig. 1 is an elevational view of the carousel toy, showing my new design;

Fig. 2 is a top plan view thereof; and

Fig. 3 is a sectional view thereof along the line 3—3 of Fig. 1, looking in the direction of the arrows.

I claim:

The ornamental design for a carousel toy, substantially as shown.

THERESA C. CHERESH.
